MATERIAL LOADING APPARATUS

Robert C. Osgood, Claremont, N. H., assignor to
 Sullivan Machinery Company, a corporation
 of Massachusetts

Application June 5, 1941, Serial No. 396,743

15 Claims. (Cl. 214—132)

This invention relates to material loading apparatus, and more particularly to improvements in the automatic centering means for the shovel of a mine car loader of the type commonly known as a muck loader.

In material loading apparatus of the type known as a mine car or muck loader, the vertically swingable shovel of the loader is usually swivelly mounted on the loader base to swing horizontally into material digging positions at either side of the path of movement of the base. The shovel is usually manually swung horizontally into its laterally located digging position, and after the shovel has been advanced into the material to be loaded it is swung upwardly to its raised dumping position. As the shovel is swung upwardly, means is oftentimes provided for automatically swinging the shovel from its laterally located position into alinement with the loader base prior to the discharge of the material from the shovel, to assure proper discharge of the shovel contents into a mine car located immediately at the rear of the loader. Known types of such automatic self-centering means for the shovel are usually actuated directly by the shovel, so that when the shovel is swung upwardly one of its supporting arms engages an element of the centering means whereby the centering action is automatically effected by swinging movement of the shovel. Such automatic shovel centering means are usually relatively complicated, and, in certain known forms, embody a cam roller engageable with cam surfaces, so that when the shovel swings upwardly towards its discharging position the cam roller moves relative to the cam surfaces to effect automatic centering of the shovel with respect to the loader base.

An object of the present invention is to provide an improved material loading apparatus having improved automatic centering means for the shovel embodying advantages over known types of centering devices. Another object is to provide an improved loading apparatus having improved means for automatically centering the shovel thereof from a laterally located position with respect to the loader base during movement of the shovel from its lowered digging position toward its raised material discharging position. Still another object is to provide an improved mine car loader having improved means for automatically alining the shovel relative to the loader base as the shovel is moved from its lowered digging position toward its raised dumping position, embodying automatic

centering means actuated by an element of the shovel moving means. A further object is to provide an improved mine car loader of the pivoted shovel type having improved means actuated by an element of the shovel swinging means for automatically effecting alinement of the shovel relative to the base, so that proper discharge of the shovel contents into a mine car located at the rear of the loader is assured.

Other objects and advantages of the invention will, however, hereinafter more fully appear as the description proceeds.

In the accompanying drawings there is shown for purposes of illustration one form which the invention may assume in practice.

In these drawings:

Fig. 1 is a side elevational view of a mine car loader in which an illustrative form of the invention is embodied.

Fig. 2 is a plan view of the mine car loader shown in Fig. 1, with parts omitted to facilitate illustration.

Fig. 3 is a view in longitudinal vertical section taken substantially on line 3—3 of Fig. 2.

Fig. 4 is an enlarged cross sectional view taken substantially on line 4—4 of Fig. 3.

Fig. 5 is an enlarged detail vertical sectional view taken on line 5—5 of Fig. 3.

Fig. 6 is an enlarged horizontal sectional view taken on line 6—6 of Fig. 3.

Fig. 7 is a detail vertical sectional view taken on line 7—7 of Fig. 6.

Fig. 8 is a detail cross sectional view taken on line 8—8 of Fig. 7.

In this illustrative embodiment of the invention the improved automatic shovel centering means is embodied in a mine car loader of the type commonly known as a muck loader for loading loose rock or muck in metal mines. It will be evident, however, that the invention may be embodied in loading apparatus of various other types.

The mine car loader disclosed herein may be of the same general character as that described in my copending application Serial No. 324,826, filed March 19, 1940, now matured into Patent No. 2,268,570, patented January 6, 1942, and comprises a self-propelled base, herein a truck frame 1 mounted on wheels 2 adapted to travel along a trackway 3 laid on the mine floor. The wheeled truck frame has swivelly mounted thereon, for horizontal swinging movement relative thereto, an upper frame or turntable 4 on which the shovelling mechanism is mounted. This swivelled upper frame 4 has vertical side plates 5, 5

and is swivelled on bearings 6 (see Fig. 5) supported by a stationary vertical shaft 7 fixed to the truck frame. The driving means for the truck wheels comprises a conventional reversible fluid operated motor 8 arranged on the truck frame beneath the swivelled frame 4, and the loader may be propelled in either of opposite directions along the trackway by this motor. The motor 8 is controlled by a conventional reversing valve 9 operated through a flexible operating shaft 10 by a control handle 11.

Mounted on the swivelled frame 4, between the vertical side plates 5, 5 thereof, is a shovel 13 supported by side arms 14, 14 having integral segmental portions 15. The shovel side arms are movably supported by guide members 16, and guiding rollers 17, journaled on the shovel side arms 14 to turn on axes coincident with the roller supporting axes, are mounted in the guideways thereof. The rollers 17 engaging the guideways of the guide members 16 provide a rolling pivotal support for the shovel as the latter is swung about its moving fulcrum point, as will later be explained.

As fully described in the copending application above referred to, the segmental portions 15 of the shovel supporting arms have arcuate cable guiding grooves for receiving pairs of spring tensioned flexible cables 18, 18 and 19, 19 each secured at one end to the frame 4 and at the opposite end to a segmental portion 15, and these pairs of cables serve to compel swinging movement of the shovel arms, thereby to effect movement of the shovel arms bodily longitudinally as they are swung, to provide in effect a moving fulcrum point for the shovel and to serve to effect swinging movement of the shovel in a curvilinear path whose rate of change of direction is non-constant as it moves from its lowered digging position upwardly to its raised dumping position and vice versa.

The means for raising and lowering the shovel 13 on its rolling pivotal mounting comprises flexible side chains 20 wound on drums 21, and the chains are fastened to the segmental portions of the shovel arms at 22 (Fig. 3). The intermediate portions of the chains 20 pass around arcuate guide surfaces on the segmental arm portions, so that when the chains are wound in by their drums the shovel is swung upwardly and rearwardly. A reversible fluid actuated motor 23, similar to the truck propelling motor 8, is mounted on the swivelled frame 4 for effecting drive of the shovel raising drums 21, and this motor has connected to its power shaft a sprocket 24 connected by an endless drive chain 25 to a chain sprocket 26 keyed to a horizontal shaft 27. This shaft extends transversely between the vertical side plates 5, 5 and is suitably journaled thereon, and the drums 21 are keyed to the shaft 27 and driven thereby. The motor 23, like the motor 8, is controlled by a conventional reversing valve 28 having a control handle 29.

Secured to the vertical side plates 5, 5 of the swivelled frame 4, near the rear ends thereof, is a transverse frame member 30 carrying conventional shock absorbing or buffer springs 31, and when the shovel is swung upwardly on its rolling pivotal mounting and moves past its center of gravity, the shovel side arms engage these buffer springs to provide a cushioned stop for the shovel. When the rearward movement of the shovel is abruptly stopped by the buffer springs, the shovel contents are discharged into a mine car M (Fig. 1) located on the trackway 3.

immediately at the rear of the latter. When the shovel assumes its rearmost dumping position against the buffer springs, as indicated in dotted lines at A in Fig. 1, and it is desired to return the shovel to its lowered digging position, as indicated in full lines at B in that figure, the shovel must be initially moved forwardly past its center of gravity before it will drop down under its own weight, and for initiating this return movement a fluid operated return cylinder 32 is supported by the transverse frame member 30, and this cylinder contains a reciprocable piston (not shown) having a plungerlike piston rod 33 (Fig. 3) extending forwardly through the front cylinder head. This cylinder may be operated to move the shovel forwardly past its center of gravity so that the shovel may thereafter swing downwardly towards its lowered digging position under the control of the drums 21 and side chains 20. Prior to the return movement of the shovel, the reversing valve 28 for the motor 23 is operated to effect reversal of the latter, and by properly controlling the motor 23 the downward movement of the shovel may be controlled. This return movement initiating means is likewise fully described in the above mentioned copending application.

The improved automatic means for centering the shovel relative to the truck frame as the shovel swings upwardly from its lowered digging position toward its raised dumping position comprises a pair of parallel racks 35, 35 located at opposite sides of the frame swivel axis and guided for movement longitudinally relative to the swivelled frame 4 in parallel guideways 36, 36 secured to the frame. Meshing with these racks are spur pinions 37, 37 secured to the opposite ends of a horizontal shaft 38. This shaft extends transversely of the swivelled frame 4 between the vertical side plates and is journaled in bearings 39 suitably secured to the frame. The spur pinions 37 are driven from the drum drive shaft 27, and keyed to the latter is a sprocket 40 connected by an endless drive chain 41 to a chain sprocket 42 secured to the shaft 38. In lieu of the racks and pinions any form of mechanically interengaging actuating elements may be employed without departing from the spirit of the invention, such as cooperating screw and nut elements. Also the pinions may be driven from elements of the shovel swinging means other than the shaft 27. It is accordingly evident that when the chain drums 21 are driven to wind in the chains to raise the shovel the spur pinions 37 are driven through the chain and sprocket connection 40, 41, 42 in a direction to move the racks 35 concurrently in a forward direction within their guideways, and when the chain drums are driven in a direction to permit lowering of the shovel the spur pinions 37 are driven in a direction to effect concurrent rearward movement of the racks within their guideways. Pivotally connected at 43 to the racks 35, at their rearward ends, are arms 44 provided with elongated longitudinal slots 45, and projecting within these slots are vertical abutment pins 46 fixed to the truck frame. The abutment pins 46 project upwardly through arcuate slots 47 in the swivelled frame 4, and these slots permit turning of the swivelled frame relative to the relatively stationary pins, in an obvious manner. It will thus be seen that when the shovel is in a laterally located digging position indicated in dotted lines in Fig. 2 and the motor 23 is operated to drive the chain drums 21 in

a direction to raise the shovel, the racks 35 are moved forwardly in their guidways relative to the swivelled frame, and the effective one of the slotted arms 44 engages its cooperating abutment pin to move the swivelled frame 4, together with the shovel supported thereby, into alignment with the truck frame, so that when the shovel is raised from its lowered digging position toward its raised dumping position it is automatically brought into alignment with the mine car M to assume proper discharge of the shovel contents into the mine car. When the shovel is in alignment with the loader base and the shovel is in its raised position, the swivelled frame 4 is locked against swivel movement by the slotted arms cooperating with the abutment pins. When the shovel approaches its raised discharging position, it is abruptly stopped by the buffer springs 31 and the shovel contents are discharged into the waiting mine car, and thereafter the fluid cylinder 32 is operated to initiate return movement of the shovel. When the shovel again assumes its lowered digging position shown in full lines in Fig. 1, the slotted arms 44 assume the position shown in Fig. 2, and at that time the arms are out of locking engagement with the pins so that the swivelled frame may be manually turned freely horizontally about its swivel relative to the loader base. It is accordingly evident that the automatic centering means is so coordinated with the shovel swinging means that the shovel is always automatically aligned with the loader base prior to the discharge of the shovel contents into the min car. In the event the loader is operating on a curved trackway, one or the other of the slotted arms 44 may be readily disconnected from its operating rack simply by removing one of the arm pivot bolts, thereby to render the automatic centering means ineffective, in a manner which will be readily understood by those skilled in the art. As the general mode of operation of the mine car loader disclosed herein is fully described in the above mentioned copending application, further description of the mode of operation of the loader is herein unnecessary.

As a result of this invention it will be noted that an improved mine car or muck loader is provided having improved and simplified means or automatically centering the shovel with respect to the loader base as the shovel moves upwardly towards its raised dumping position. It will further be noted that by operating the automatic centering means through elements of the shovel swinging means, automatic alignment of the shovel with respect to the loader base is assured. By the provision of the sliding racks and slotted arms cooperating with relatively stationary abutment pins, the means for centering the shovel is simplified and made more rugged than previously known mechanical centering devices while at the same time a positive aligning and centering action is attained. Other uses and advantages of the invention will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a shovelling mechanism, the combination comprising a portable base, a frame swivelled on said base to turn horizontally relative thereto, a shovel, a shovel support pivotally mounted on said swivelled frame to swing in a vertical direction relative thereto, means for effecting vertical swinging movement of said shovel support, and means operated by an element of said shovel swinging means independently of any direct actuation by said shovel or its support for automatically centering the shovel relative to the base as said shovel swings vertically, said automatic centering means including a pair of oppositely acting centering-effecting elements guided for concurrent movement in the same direction relative to said frame, and cooperating abutment elements on said base.
2. In a shovelling mechanism, the combination comprising a portable base, a frame swivelled on said base to turn horizontally relative thereto, a shovel pivotally mounted on said swivelled frame to swing in a vertical direction relative thereto, means for effecting vertical swinging movement of said shovel, and means operated by an element of said shovel swinging means for automatically centering the shovel relative to the base as said shovel swings vertically, said automatic centering means including a pair of oppositely acting centering-effecting elements guided for concurrent movement in the same direction relative to said frame, spaced abutment elements on said base with which said centering-effecting elements respectively cooperate, and actuating means for said centering-effecting elements including relatively rotatable mechanically interengaged actuating elements, certain of which are operatively connected to said centering-effecting elements.
3. In a shovelling mechanism, the combination comprising a portable base, a frame swivelled on said base to turn horizontally relative thereto, a shovel pivotally mounted on said swivelled frame to swing in a vertical direction relative thereto, means for effecting vertical swinging movement of said shovel, and means operated by an element of said shovel swinging means for automatically centering the shovel relative to the base as said shovel swings vertically, said automatic centering means including a pair of oppositely acting centering-effecting elements guided for concurrent movement in the same direction relative to said frame, cooperating abutment elements on said base, and actuating means for said centering-effecting elements including a pair of racks and pinions meshing with said racks respectively.
4. In a shovelling mechanism, the combination comprising a portable base, a horizontal turntable swivelled on said base to turn about a vertical axis, a shovel pivotally mounted on said turntable to swing in a vertical direction relative thereto from a lowered digging position to a raised dumping position, means for vertically swinging said shovel, and means driven by an element of said shovel swinging means for rotating said turntable automatically to center the shovel relative to said base as said shovel approaches its raised dumping position including oppositely acting, centering-effecting elements and spaced abutment elements with which centering-effecting elements respectively cooperate.
5. In a shovelling mechanism, the combination comprising a portable base, a horizontal turntable swivelled on said base to turn about a vertical axis, a shovel pivotally mounted on said turntable to swing in a vertical direction relative

thereto from a lowered digging position to a raised dumping position, means for vertically swinging said shovel, and means driven by an element of said shovel swinging means for rotating said turntable automatically to center the shovel relative to said base as said shovel approaches its raised dumping position, said automatic centering means including oppositely acting centering-effecting elements mounted on said turntable for concurrent movement in the same direction relative thereto and spaced abutment elements on said base with which said centering-effecting elements respectively cooperate.

6. In a shovelling mechanism, the combination comprising a portable base, a horizontal turntable swivelled on said base to turn about a vertical axis, a shovel pivotally mounted on said turntable to swing in a vertical direction relative thereto from a lowered digging position to a raised dumping position, means for vertically swinging said shovel, and means driven by an element of said shovel swinging means for rotating said turntable automatically to center the shovel relative to said base as said shovel approaches its raised dumping position, said automatic centering means including centering-effecting elements guided for concurrent rectilinear movement in the same direction along parallel paths located at the opposite sides of the turntable axis.

7. In a shovelling mechanism, the combination comprising a portable base, a horizontal turntable swivelled on said base to turn about a vertical axis, a shovel pivotally mounted on said turntable to swing in a vertical direction relative thereto from a lowered digging position to a raised dumping position, means for vertically swinging said shovel, and means driven by an element of said shovel swinging means for rotating said turntable automatically to center the shovel relative to said base as said shovel approaches its raised dumping position, said automatic centering means including a pair of parallel racks and gears meshing with said racks respectively.

8. In a shovelling mechanism, the combination comprising a portable base, a horizontal turntable swivelled on said base to turn about a vertical axis, a shovel pivotally mounted on said turntable to swing in a vertical direction relative thereto from a lowered digging position to a raised dumping position, means for vertically swinging said shovel, and means driven by an element of said shovel swinging means for rotating said turntable automatically to center the shovel relative to said base as said shovel approaches its raised dumping position, said automatic centering means including a pair of parallel racks and gears meshing with said racks respectively, said gears being disposed on aligned axes disposed transversely of said turntable.

9. In a shovelling mechanism, the combination comprising a portable base, a horizontal turntable swivelled on said base to turn about a vertical axis, a shovel pivotally mounted on said turntable to swing in a vertical direction relative thereto from a lowered digging position to a raised dumping position, means for vertically swinging said shovel, and means driven by an element of said shovel swinging means for rotating said turntable automatically to center the shovel relative to said base as said shovel approaches its raised dumping position, said automatic centering means including oppositely acting centering-effecting elements arranged at the opposite sides of a vertical plane including the turntable axis and movable concurrently rectilinearly in the same direction upon swinging of said shovel in one direction.

10. In a shovelling mechanism, the combination comprising a portable base, a horizontal turntable swivelled on said base to turn about a vertical axis, a shovel pivotally mounted on said turntable to swing in a vertical direction relative thereto from a lowered digging position to a raised dumping position, means for vertically swinging said shovel, and means driven by an element of said shovel swinging means for rotating said turntable automatically to center the shovel relative to said base as said shovel approaches its raised dumping position, said automatic centering means including oppositely acting centering-effecting elements arranged at the opposite sides of a vertical plane including the turntable axis and movable concurrently rectilinearly in the same direction upon swinging of said shovel in one direction and spaced abutments on said base with which said centering-effecting elements respectively cooperate.

11. In a shovelling mechanism, the combination comprising a portable base, a turntable on said base, a shovel pivotally mounted on said turntable to swing in a vertical direction relative thereto, means for swinging said shovel in a vertical direction including a motor, and means driven by said motor for automatically aligning said shovel with respect to said base as the shovel swings vertically toward its discharge position, said aligning means comprising spaced abutments stationary with respect to said base, and members mounted on said turntable and movable longitudinally relative to the latter, one of said longitudinally movable members being engageable with one of said abutments when said turntable is turned to locate said shovel at one side or the other of said base and said members being movable concurrently along parallel paths in the same direction with respect to the turntable as said shovel swings vertically.

12. In a shovelling mechanism, the combination comprising a portable base, a frame swivelled on said base to turn horizontally relative thereto, a shovel pivotally mounted on said swivelled frame to swing in a vertical direction relative thereto, means for effecting vertical swinging movement of said shovel, and means operated by an element of said shovel swinging means for automatically centering the shovel relative to the base as said shovel swings vertically, said automatic centering means including a pair of oppositely acting centering-effecting elements guided for concurrent movement in the same direction relative to said frame, cooperating abutment elements on said base, and actuating means for said centering-effecting elements including rack-means and gear-means meshing with said rack-means.

13. In a shovelling mechanism, the combination comprising a portable base, a horizontal turntable swivelled on said base to turn about a vertical axis, a shovel pivotally mounted on said turntable to swing in a vertical direction relative thereto from a lowered digging position to a raised dumping position, means for vertically swinging said shovel, and means driven by an element of said shovel swinging means for rotating said turntable automatically to center the shovel relative to said base as said shovel approaches its raised dumping position, said automatic centering means including rack and gear means.

14. In a shovelling mechanism, the combina-

tion comprising a portable base, a frame swivelled on said base to turn horizontally relative thereto, a shovel pivotally mounted on said swivelled frame to swing in a vertical direction relative thereto, means for effecting vertical swinging movement of said shovel, and means operated by an element of said shovel swinging means for automatically centering the shovel relative to the base as said shovel swings vertically, said automatic centering means including a pair of oppositely acting, mechanically actuated, centering-effecting elements guided along parallel paths for concurrent movement in the same direction and cooperating abutment elements, certain of said centering-effecting and abutment elements remaining stationary while the others are movable during centering of the shovel.

15. In a shovelling mechanism, the combination comprising a portable base, a frame swivelled on said base to turn horizontally relative thereto, 20

a shovel pivotally mounted on said swivelled frame to swing in a vertical direction relative thereto, means for effecting vertical swinging movement of said shovel, and means operated by an element of said shovel swinging means for automatically centering the shovel relative to the base as said shovel swings vertically, said automatic centering means including a pair of oppositely acting centering-effecting elements guided 5 for concurrent movement in the same direction and cooperating abutment elements, certain of said centering-effecting and abutment elements remaining stationary while the others are movable during centering of the shovel, and actuating means for said centering-effecting elements including cooperating relatively movable, mechanically interengaged, actuating elements, certain of which are operatively connected to said centering-effecting elements.

ROBERT C. OSGOOD.
